[57] CLAIM

The ornamental design for a clothes treating apparatus, as shown and described.

DESCRIPTION

FIG. 1 is a perspective view of a clothes treating apparatus showing our new design

FIG. 2 is a front view of a clothes treating apparatus showing our new design; and,

FIG. 3 is a side view of a clothes treating apparatus showing our new design.

The side of the clothes treating apparatus opposite to that shown in the drawing is a mirror image thereof. The top, bottom and rear of the clothes treating apparatus form no part of the claimed design.
